UNITED STATES PATENT OFFICE.

WALTER ST. CLAIR AND BEDFORD S. ROBERTSON, OF ROCKY MOUNT, VIRGINIA.

STOMACH-PUMP ATTACHMENT.

1,313,610.

Specification of Letters Patent.

Patented Aug. 19, 1919.

Application filed September 23, 1916. Serial No. 121,839.

To all whom it may concern:

Be it known that we, WALTER ST. CLAIR and BEDFORD S. ROBERTSON, citizens of the United States, residing at Rockymount, in the county of Franklin, State of Virginia, have invented a new and useful Stomach-Pump Attachment, of which the following is a specification.

By way of explanation it may be stated that 10 when a stomach pump is being used on a patient who is in convulsions, or is otherwise incapable of subjective control of his acts, the jaws of the patient frequently close on the inlet tube of the stomach pump, thereby 15 choking off the inlet tube, and rendering the entire pump useless. Further, under the conditions above mentioned, the inlet tube of the stomach pump frequently is bitten apart, and the patient swallows the severed 20 end.

In view of the foregoing, the object of the invention is to provide novel means, mounted on the inlet tube of a stomach pump, whereby the patient will be prevented 25 from closing his jaws on the inlet tube, and choking the inlet tube or severing it.

It is within the province of the disclosure to improve generally and to enhance the utility of devices of that type to which the 30 present invention appertains.

With the above and other objects in view which will appear as the description proceeds, the invention resides in the combination and arrangement of parts and in the 35 details of construction hereinafter described and claimed, it being understood that changes in the precise embodiment of the invention herein disclosed, can be made within the scope of what is claimed, without departing from the spirit of the invention.

In the accompanying drawings:—

Figure 1 is a side elevation of a stomach pump to which the device claimed has been applied, parts being broken away, parts appearing in section, and the connection which is adapted to bridge the pumping mechanism being shown out of operative relation to the pumping mechanism.

Fig. 2 is an elevation wherein a modified 50 form of the invention appears, parts being shown in section;

Figs. 3, 4 and 5 are views similar to Fig. 2 but showing, each, a modification in the invention;

Fig. 6 is a fragmental elevation showing a hinged connection used in Fig. 3; and

Fig. 7 is a fragmental elevation showing a hinge used in Fig. 5.

Fig. 8 is a transverse section showing a further modification in the invention, the pumping mechanism being omitted, and the member which is adapted to bridge the pumping mechanism being shown in part only.

In the drawings, there is shown a stomach 65 pump comprising an inlet tube 1, an outlet tube 2, and an intermediate bulb pump 3 connecting the tubes. The pump, however, may be of any desired form.

In one form of the invention, there is provided an incompressible tubular guard 4, made of metal or some other substance having sufficient strength so that the tube 4 cannot be crushed between the patient's jaws. The guard 4 is equipped with an outstanding flange 5 having openings 6 adapted to receive a band or other connector 7, which may be elastic. The band 7 passes around the head of the patient and holds the guard 4 in place. Owing to the fact that, as shown 80 in the drawings, the guard 4 is of tapered form, the inlet tube 1 of the stomach pump may be introduced readily through the guard. The guard is of sufficient diameter so that the inlet tube 1 may be adjusted 85 longitudinally. The flange 5 not only serves as a point of attachment for the head band 7, but, also, serves to protect the hand of the operator, should the patient vomit. If desired, the tubular incompressible guard 4 90 may be surrounded by a resilient protector 8, such as a tube of rubber, the function of the protector 8 being to prevent the teeth of the patient from being injured when the jaws close together toward the incompressible guard 4. The flange 5 serves to prevent 95 the patient from swallowing the guard tube 4.

In Fig. 2, the numeral 9 designates the inlet tube of a stomach pump, the outlet tube 100 is shown at 10, and the pump proper appears as 11. The numeral 12 denotes an incompressible guard tube having a resilient protector 14. The guard tube 12 is equipped with a curved extension 15 adapted to span 105 the pump 11. Connected with the extension 15 is a flexible element 16 looped around the outlet tube 10 as shown at 17. The numeral 18 designates a detachable connection on the end of the flexible element 16, whereby the loop 17 may be formed. Owing to the construction above described, the guard 110

tube may be held in a retracted position, when not in use.

As shown in Fig. 3, there is provided an incompressible tubular guard 19 surrounded by a protector 20. An arm 21 is hinged at 22 to the guard 19. A flexible element 23 of the kind hereinbefore described is attached to the free end of the arm 21 and is held at one end in the form of a loop 24 by a connector 25, for the purpose hereinbefore set forth. The hinged connection 22 preferably embraces co-operating ears 26 on the parts 19 and 21, and a pintle 27 extended through the ears.

In the form shown in Fig. 4, the incompressible guard tube is shown at 28 and is surrounded by a resilient protector 29. In this form of the invention, the flexible element 30 is connected directly with one end of the guard tube 28 and is held at one end, releasably, in a loop 31, as hereinbefore described. As indicated at 30^b, the construction last above described may be used in connection with that form which is delineated in Fig. 1.

As shown in Fig. 5, the incompressible guard tube appears at 32 and is surrounded by a resilient protector 33. One end of the guard tube 32 is equipped with a projecting eye 34 to which an arm 35 is pivoted by means of an eye 36, the arm 35 in the present instance being in the form of a piece of wire. The arm 35 at its free end carries, as before, a flexible element 37 formed into a loop 38 as hereinbefore set forth.

Although the flange 5 has been shown only in connection with that form of the invention which is depicted in Fig. 1, it will be understood that the flange may be applied to the other forms of the invention if desired.

It will be understood that in all forms of the invention, the inlet tube is freely adjustable, longitudinally, through the incompressible guard.

In Fig. 8 of the drawings, the incompressible guard appears at 50 and is surrounded by a protector 51 of the kind hereinafter set forth. The guard 50 has a bell-shaped 50 end 52 formed into a circumscribing rib 53

and a peripheral flange 54. A plate 55 abuts against the rib 53 and lies within the contour of the flange 54. Securing elements 56 which may be rivets unite plate 55 with the rib 53. Rivets 56 carry strips 57 supporting buttons 58 adapted to be connected with a flexible element like that shown in Fig. 1. The plate 55 is provided with a reflecting surface on its outer face, so that by reversing the device on the tube 1, this reflecting surface may be used to illuminate the mouth and throat of the patient. As indicated at 30^c, the flexible element 30 and attendant parts, of Fig. 4, may be used in connection with that form which is depicted in Fig. 8.

An inspection of the drawings will render it evident that the device forming the subject matter of this application may be removed readily from a stomach pump, to permit sterilization and cleaning.

Having thus described the invention, what is claimed is:—

A stomach pump comprising an inlet tube; an outlet tube; a pumping mechanism interposed between the tubes and connecting the tubes, the pumping mechanism being of greater diameter than either tube; an incompressible tubular guard wherein the inlet tube slides; and a connection having one of its ends attached to the guard, the connection bridging the pumping mechanism and terminating at its other end in a releasable loop engaged around the outlet tube and of smaller diameter than the pumping mechanism, the pumping mechanism having a three-fold office, in that it constitutes a liquid-handling means, a stop limiting the backward movement of the guard, and a stop for the loop thereby limiting longitudinal movement of the connection and a forward movement of the guard.

In testimony that we claim the foregoing as our own, we have hereto affixed our signatures in the presence of two witnesses.

WALTER ST. CLAIR.
BEDFORD S. ROBERTSON.
